UNITED STATES PATENT OFFICE.

OTTO RICHARD SIELAFF, OF LIVINGSTON, MONTANA.

SHOW-CARD HOLDER.

1,396,892.

Specification of Letters Patent. Patented Nov. 15, 1921.

Application filed June 6, 1921. Serial No. 475,382.

To all whom it may concern:

Be it known that I, OTTO RICHARD SIELAFF, a citizen of the United States of America, and a resident of Livingston, county of Park, 5 and State of Montana, have invented certain new and useful Improvements in Show-Card Holders, of which the following is a specification.

The main objects of this invention are to 10 provide a show card holder having an improved form and arrangement of parts for visibly supporting a show card above the articles of merchandise which it displays; to provide improved means for removably sup- 15 porting the show card in the holder; and to provide improved means for detachably securing the holder to the side of a merchandise tray or similar receptacle.

An illustrative embodiment of this in- 20 vention is shown in the accompanying drawings, wherein—

Figure 1 is a perspective view of the card holder.

Fig. 2 is a plan, partly broken away, showing the holder applied to a merchandise tray.

Fig. 3 is a vertical section of the holder, showing the tray partly broken away.

Many of the price card holders, which are 30 now in common use for supporting a price tag on a merchandise tray or sales counter, are objectionable in that the tag is held in a position where it may be inadvertently covered by the merchandise which the tag 35 displays. The present invention overcomes this objectionable feature by providing a holder having a base which may be covered by the merchandise, and having a back member formed to support a price tag in a 40 visible position above the tray.

In the form shown, the price card holder is made of a single piece of sheet metal, and comprises a rectangular base 1 and a back plate 2 disposed at substantially right angles 45 to each other.

The back 2 is bent to provide a shoulder

or ledge 3, which extends across the back substantially parallel to the base, for supporting a price card or tag 4. The side edges of the back above the ledge 3 are bent 50 forwardly and inwardly to form a pair of vertically disposed guides 5 for engaging the tag.

Struck out from the back plate is a lug 6 which extends rearwardly and downwardly 55 in spaced relation to the plane of the back. The lug 6 and back plate 2 form a clip which is adapted to straddle one of the side walls of a merchandise tray 7 of standard height for detachably securing the holder to the 60 tray while the base rests on the bottom thereof.

When the device is in use, the holder may be either placed upon a sales counter or in a merchandise tray as shown in Fig. 3. In 65 either case the price tag is supported in a position where it is not obscured from view by the merchandise which it displays.

It is to be understood that some of the details of the construction shown may be altered or omitted without departing from the spirit of this invention as defined by the following claim.

I claim:

A sheet metal show card holder comprising 75 a base adapted to rest within a merchandise tray, a back bent up from said base and disposed at substantially right angles thereto, a ledge bent out from said back above and parallel to said base for supporting 80 a show card in a visible position above the walls of said tray, the side edges of said back being bent inwardly to form a pair of spaced guides for engagement with said show card, and a lug struck out from said 85 back, said lug and back being relatively arranged to form a clip adapted to straddle one of the side walls of said tray.

Signed at Chicago this 1st day of June, 1921.

OTTO RICHARD SIELAFF.
